IGNITION DEVICE

Elmer G. Steffen, Milwaukee, Wis., assignor to
 Milwaukee Gas Specialty Company, Milwaukee,
 Wis., a corporation of Wisconsin

Application December 4, 1931, Serial No. 578,943

10 Claims. (Cl. 158—115)

My invention relates to igniters for gas burners and contemplates an improvement in such devices adapted to insure lighting of the burners even under conditions of extremely low gas pressure or while using inferior grades of gas.

It is well known that, in the use of gas burners, it is very difficult to light the burner, particularly when using a pilot light, under conditions of low gas pressure, as for instance when the burner is used to deliver a minimum amount of heat.

My invention provides means for insuring ignition of the gas issuing from the burner under conditions of low pressure or when poorer grades of gas are being burned.

My invention also materially expedites the operation of igniting the burner from a pilot light. A device embodying my invention may be easily raised or removed for cleaning and repair of the device and of the heater with which it is utilized.

Other and further features and objects of the invention will be more apparent to those skilled in the art upon a consideration of the accompanying drawing and following specification, wherein is disclosed a single exemplary embodiment of the invention with the understanding, however, that such changes may be made therein as fall within the scope of the appended claims without departing from the spirit of the invention.

In said drawing:

Figure 1 is a plan view of an arrangement of burners and igniter embodying my invention; and

Figure 2 is a partial sectional view taken substantially on the line 2—2 of Figure 1, looking in the direction indicated by the arrows.

The present invention deals particularly with the so-called "gravity" type of igniter in which a sheltered pilot flame is burning at all times. These devices are so constructed that when the gas is turned on at a burner a portion of the gas is led from the burner to the pilot flame where it is ignited and burned in such a manner that the flame travels back to the burner. The invention is particularly shown and described in an embodiment of such an igniter adapted for use with open flame burners as for instance the burners used in gas ranges, stoves and the like, but may be used or modified for use with other types of burners, other kinds of fuel and other igniters.

Referring now to the drawing for a more complete disclosure of the invention, there is shown at 10 a gaseous fuel manifold of the usual construction. The manifold is connected by means of a pipe (not shown) to a burner 11 which is of the usual construction except that a pipe fit-

ting 12 is threaded into the end of one of the arms of the burner 11 and a small torch head or spud 13 is threaded into the pipe fitting. The spud is provided with two ports 25 and 26 at its upper end arranged to direct gas issuing therefrom into two opposed streams which, when ignited form two flames 14 and 15 one of which, 14, burns directly over the outermost ports of the burner, to which the spud is attached, and the other of which, 15, is directed toward the pilot burner, hereinafter described.

A substantially circular or cup-shaped base 16 is attached to the fitting 12, as by utilizing the spud 13 as a bolt, and a cylindrical or cup-shaped hood or trap 17 is telescoped over the base 16 in loose engagement therewith to provide a chamber for trapping the gas issuing from the spud 13, and housing the spud. Openings 18 are provided in the side wall of the trap to furnish oxygen to the flames to support combustion. A vent 19 is provided in the top of the trap to permit the products of combustion from the flames to pass out of the trap, and another opening 21 is provided in the side wall of the trap to permit the flame 14 to issue therefrom. A circular opening 22 is provided in the side wall of the trap in a location opposite to and above the opening 21 and a thin walled pipe 23 is inserted in the opening and fastened to the opposite portion of the wall of the trap 17 by means of a tongue 24 which projects through a suitable slot in the wall. The lower half of the portion of the pipe 23 which projects inside the trap 17 is cut away in order that the gas from the spud 13 may have easy access to the interior of the pipe.

A pipe fitting 31 is disposed in an opening in the manifold 10 and a pipe or lighter tube 32 is secured to the fitting 31 by means of a bushing or pilot body 33. The outer end of the pipe or lighter tube is preferably threaded in order that a cup-shaped pilot hood base 34 may be secured thereto by means of nuts 35.

The end of the pipe 32 has a torch head 36 thereon, which is provided with a burner or pilot tip 37 having one or more ports therein to permit the escape of gas. The passageway through the fitting 31, the pipe 32 and the tip 37 is always open so that when gas escaping through the ports in the tip is ignited a pilot flame 38 is provided which burns constantly as long as gas is supplied to the manifold 10. The fitting 31 has a pilot adjusting screw 39.

A cylindrical or cup-shaped cover or hood 39 is telescoped over the base 34 and one portion of the wall rests on the pipe 32. The hood is

adapted to cover the pilot flame 38 to prevent the flame from being quenched by external air currents or the like. Openings 41 are provided in the cover 39 and the base 34 to permit entrance 5 of air into the hood so that the flame may have oxygen to support combustion. Another opening 42 is provided in the top of the hood to permit the escape of the products of combustion.

A plurality of circular openings 43 are provided 10 in the side walls of the hood and short sections of thin walled pipe 44 are fastened to project through the openings into the hood. The inner end of the pipe 44 is preferably cut at an angle so that the upper portion projects further into the 15 hood than does the lower portion. The pipe is adapted to be secured to the walls of the hood by means of upstruck portions or lugs 45, which are adapted to loosely engage the wall of the hood at the openings 43, forming a hinge mounting permitting the respective tubes to be raised or pivoted 20 about the point of engagement so that the burner can be either cleaned or removed.

A tube or adjusting sleeve 47 is loosely telescoped over the pipes 23 and 44 and thus provides 25 for relative movement of the trap 17 with respect to the hood 39 to provide for differences in the dimensions of the heaters or stoves with which the lighting device is to be used. A slot 48 is provided on the under side of the tube 47 to permit 30 the entrance of air to the tube in order to support combustion of gas within the tube, and lugs 49 and 51 on the outer ends of the respective pipes 23 and 44 are located within the slot 48 to prevent 35 relative rotation of the sleeve and other parts of the device.

In operation, the pilot flame, when once ignited, 40 burns continuously. If the valve controlling the entrance of the gas into the burner 11 is turned on gas passes from the manifold 10 into the burner 11 and out through the burner ports and through the ports in the spud 13. The gas issuing 45 from the inner port of the spud 13 passes upwardly into the trap 17 and into the pipe 23. The pipes 23, 47 and 44 are inclined slightly upwardly from the trap to the hood 39 and the gas passes through the pipe and into the hood 39 above the pilot flame 38. Since the inner ends 50 of the pipe 44 are cut at an angle to cause the upper end thereof to project to a position almost directly above the pilot flame 38 the gas passing through the pipes 23, 47 and 44 comes into close proximity to the open pilot flame and is readily ignited. Since the gas within the pipes 23, 47 and 44 has been mixed with air from the openings 55 18 and 48, the flame is carried quickly back to form the flame 15 at the port 26 of spud 13. This flame is relayed to the gas issuing from the port 25 to form the flame 14 which, by reason of its proximity to the burner 11 quickly ignites the 60 gas issuing therefrom.

In my device the gas used for igniting purposes 65 is trapped, mixed with air and directed to a position directly over the pilot flame where it is readily ignited. The flame is carried to the burner by means, including a relay burner, which insures ignition even if gas under low pressure or of poor burning quality is used. The hinged construction of the pipe 44 permits the entire trap and tube structure to be raised for cleaning and adjustment of the stove and ignition, which is a 70 material advantage. Obviously my device may be duplicated for use with a plurality of burners.

The hood or trap 17, in conjunction with the outer end of the pipe or tube 23, protects the torch head 13 against quenching as, for example, by

liquid boiling over a vessel on a burner of the range.

Although I have described a specific embodiment of my invention, it is apparent that modifications may be made by those skilled in the art. Such modifications may be made without departing from the spirit and scope of my invention as set forth in the appended claims.

I claim as my invention:

1. In an igniting device for gas burners, 10 the combination of means for supplying a pilot flame, means extending outwardly of the burner adapted to permit the escape of gas from the burner, a trap secured over said means and supported thereby adapted to catch the escaping 15 gas, connecting means supported at one end on said trap and at the other end on said pilot flame means and adapted to carry the gas so caught to the pilot flame to cause it to be ignited and to cause the flame to pass through the connecting 20 means back to the trap, and means cooperating with an opening in said trap to cause the flame in the trap to be relayed to the burner.

2. An ignition device comprising a structure for providing a pilot flame, a burner, a fitting on the 25 burner, a spud on the fitting having two opposed ports therein, a trap, and a tubing structure supported by said trap for connecting the trap with the pilot flame structure, said trap being disposed over the spud to trap the gas issuing from one 30 of the ports thereof and having an opening therein to permit gas issuing from the other port of the spud to pass outwardly over the burner ports.

3. In an ignition device, the combination of a 35 pilot burner, a base and a hood for said pilot burner, a burner, a fitting in the burner, a spud in the fitting having two opposed ports therein, a base secured to the fitting, a trap secured to the 40 base and covering the spud, a tube projecting into the trap, a tube projecting into the hood and a connecting sleeve for connecting the two tubes whereby gas issuing from the spud is conducted to the pilot flame, is ignited and the flame is carried back to the trap and relayed to the burner by means of the gas issuing from the spud. 45

4. In an ignition device for gas burners, a burner including an offset extension having a spud therein, a trap supported over said spud, a structure for providing a pilot flame including 50 a hood, a connecting tube supported at one end in said hood and at the other end in said trap, and hinge means in said tube providing for disengagement of said tube from said pilot flame structure.

5. In an ignition device for gas burners, a burner having an offset extension communicating therewith, said extension having a spud therein, a trap supported over said spud and having openings therein, said spud having opposed ports, one directed into said trap and the other directed toward one of said openings, a structure for providing a pilot flame including a 60 hood, a connecting tube supported at one end in said hood and at the other end in said trap, and hinge means in said tube providing for disengagement of said tube from said pilot flame structure.

6. In an ignition device for gas burners, a burner having a communicating extension forming a torch head, a trap secured over said torch head, a tube supported by and extending laterally of said trap, a structure for providing a pilot flame including a hood, a tube extending into 70

and supported by said hood, and connecting means providing a passage between said tubes.

7. In an ignition device for gas burners, a burner having a plurality of burner ports and having a communicating extension, a torch head in said extension having opposed ports disposed in the plane of said burner ports, a cylindrical trap member secured over said head and having openings therein, one of said torch heads being directed into said member and the other of said ports being directed through one of said openings toward said burner ports, a tube supported by and extending laterally of said trap member, a structure for providing a pilot flame including a hood, a tube extending into and supported by said hood, and connecting means providing a passage between said tubes.

8. In a gas ignition device, a structure for providing a pilot flame, a burner, an extension on said burner, a tube supported at one end on said extension and having a portion overlying said extension, a second tube supported at one end on said pilot flame structure, a hinge structure on said second tube for securing it to the pilot flame structure and arranged to provide upward movement of the tube and disengagement

from said pilot flame structure, and tubular means having adjustable telescoping engagement at its ends with the adjacent ends of said tubes.

9. In a lighter, the combination of a burner, a source of fuel supply therefor, a pilot, a housing for said pilot having an opening therein, a tubular connection of uniform diameter throughout fitting loosely at one end in the opening of said housing and at the other end communicating with the burner, and integral means on the wall of said housing loosely engaged with said tubular connection for preventing accidental removal of said tubular connection from said opening.

10. In a lighter, the combination of a burner, a source of fuel supply therefor, a pilot, a housing for said pilot having an opening therein, a tubular connection fitting loosely at one end in the opening of said housing and being readily removable therefrom and communicating with said burner at the other end, and integral means on said tubular connection loosely engaged with said housing and normally preventing accidental removal of said tubular connection from said opening.
